FEED MECHANISM FOR MEDIUM FLUTER
Fleming D. Long, Chicago, Ill., assignor to Container
Corporation of America, Chicago, Ill., a corporation of
Illinois

Filed Mar. 5, 1962, Ser. No. 177,331
5 Claims. (Cl. 156—596)

This invention appertains broadly to a machine for making and producing a fluted strip utilized as a part of a corrugated board or sample and more particularly to a medium fluter for producing a sample of a corrugated strip for test purposes.

An example of such a machine is shown in my Patent No. 3,011,937, issued December 5, 1961, and in this prior patent the strips to be fluted were fed by hand into the machine and between the fluting rolls. Thus there was no assurance that the strips would all be fed in the same manner to the rolls and consequently the flutes made would be spaced different distances from the terminals of the strips. Thus the prior machine did not produce identical samples all possessing the same characteristics.

One of the primary objects of my present invention is to provide an automatic means for feeding the strips into the machine and between the fluting rolls, with the means so timed relative to the rolls that each strip will be fed in the exact same manner to and between the rolls to produce identical fluted strips.

Another salient object of my invention is to provide a simple but effective mechanism for automatically delivering strips to be fluted to a medium fluting machine embodying a novel guide for holding the strips in line and means including a slide block operating in the guide for delivering the strips to the rolls.

A further important object of my invention is to provide cam means or shoes carried by one of the fluting rolls for operating the slide block, the cams or shoes all being located in an exact same position on the roll relative to fluting teeth, so that all the strips will be fed in the same manner between the rolls and whereby teeth of the fluting rolls will initially strike at the same point on all strips relative to the terminals of the strips.

With the above and other objects in view, which will more readily appear as the nature of the invention is better understood, the same consists in the novel construction, combination and arrangement of parts hereinafter more fully described, illustrated and claimed.

One preferred and practical embodiment of the invention is shown in the accompanying drawings, in which—

FIGURE 1 is a top plan view of a medium fluter showing my novel strip feeding mechanism incorporated therewith, parts of the figure being shown broken away to illustrate structural features;

FIGURE 2 is an enlarged fragmentary top plan view showing the strip feeding mechanism;

FIGURE 3 is a vertical sectional view through the feed mechanism taken on the line 3—3 of FIGURE 1 looking in the direction of the arrows;

FIGURE 4 is a longitudinal sectional view through the feed mechanism taken on the line 4—4 of FIGURE 3 looking in the direction of the arrows;

FIGURE 5 is a detailed vertical sectional view through the feed mechanism taken on the line 5—5 of FIGURE 2 looking in the direction of the arrows and illustrating more particularly the connection between the cam operated lever mechanism and the feed slide block; and

2

FIGURE 6 is a perspective view showing one of the fluted strips produced by the machine.

Referring to the drawings in detail, wherein similar reference characters designate corresponding parts throughout the several views, letter F generally indicates one type of my improved medium fluter and G my automatic means for feeding a strip S into the machine.

For the purpose of illustrating my automatic strip feeding means G, I have shown the same connected with the 10 medium fluter F, which can be considered as the same type shown in my above mentioned patent. Thus the machine F includes a frame 10 on which is rotatably mounted intermeshing fluting rolls 11 and 12. One of the rolls, say the roll 11, is power driven. The frame 10, the rolls 11 and 12 and other parts of the machine are preferably housed in a casing 13. As my strip feeding mechanism G operates primarily with the fluting rolls 11 and 12, other parts of the machine have not been shown or described.

In practice a straight strip S is fed between the rolls 11 and 12 and the inter-meshing teeth of these rolls form a strip, now indicated by the reference character 14 in FIGURE 6 having equidistantly spaced flutes 15. As heretofore brought out, it is desirable that all of the fluted strips 14 be of identically the same configuration with the 20 end flutes 15 all spaced exactly the same from the terminals of the strips.

In order to accomplish this, I have provided my novel 25 automatic strip feeding means G. This strip feeding means G includes a pair of facing guide blocks 16 and 17. The blocks can be secured together in any preferred 30 manner, such as by the use of machine screws 18. The guide blocks 16 and 17 for a major part of their length are spaced to provide a guide slot 19 therebetween for receiving the strips S to be fluted. The block 17 at its rear 35 end is cut away as at 20 to facilitate the manual insertion of the strip S in the guide slot 19 and the inner wall of this cut-away portion inclines inwardly to form a guide face leading toward the guide slot which also aids in the leading of the strip S into the slot. The cut-away portion 40 20 also provides a space for a certain operating part of the feeder G.

The forward end of the guide blocks 16 and 17 are 45 provided with tapered noses 21 which lead between the rolls 11 and 12, as best shown in FIGURES 1 and 2 and the blocks are rigidly secured to an appropriate part of the frame 10 of the machine by machine screws 22. The guide block 16 is provided with a longitudinally extending guide way 23 in which is reciprocally mounted a slide block 24. The guide way 23 can be partially covered by a plate 50 25 which is secured in place on the guide block 16 by fastening screws 26. The inner end of the slide block 24 has formed thereon or secured thereto a strip feeding hook 27. The block 16 also has formed in its inner face a guide slot 28 for the feeding hook 27 and this guide slot 55 28 communicates with the guide way 23 for the slide block 24. Thus during reciprocation of the slide block 24 the hook 27 will be carried therewith and moved toward and away from the fluting rolls 11 and 12.

To bring about the automatic reciprocation of the slide 60 block 24, I provide an L-shaped crank 29. This crank includes a long arm 30 and a relatively short inwardly extending right angularly extending arm 31. The outer end of the arm 30 is mounted for rocking movement on a mounting bracket 32 which is secured to the guide block 17. A threaded bearing pin 33 can be utilized for rockably 65 mounting the crank 29 on the bracket 30. As best

shown in FIGURE 5, the mounting bracket 32 can extend over the strip guide slot 19 and thus function as a further means for guiding the strip and holding the same on its edge. The crank 29 at its angle is operatively connected to the slide block 24. This operative connection includes an upright pin 34 rigidly carried by the slide block adjacent to its forward end. The pin extends through a slot 35 formed in the crank. The crank is normally held in over the slide blocks by a contractile coil spring 36. The opposite ends of the spring are connected respectively to the crank and to the cover plate 25. However, the inner end of the short arm 31 of the crank extends partially over the fluting roll 11 and this end of the crank terminates in a hook 37 which cooperates with cams or shoes 38 rigidly secured to the upper face of the fluting roll 11. It is desirable to bring about an accurate operative engagement between the crank and the cams or shoes 38 and hence, the arm 31 can be mounted for limited swinging movement and adjustment on the main body portion of the crank. Hence, as illustrated (see FIGURE 2), the inner end of the crank arm 31 is mounted on a pivot 39 carried by an extension of the crank arm 30 and this extension also carries an adjusting screw 40 which extends through an arcuate slot 41 formed in the inner end of the crank arm 31. By tightening and loosening the screw 40, the arm 31 can be set in an exact selected position relative to the arm 30 and the operating cams or shoes 38. The position of the cams or shoes 38 on the fluting roll 11 can vary according to the length of the strip S, that is more or less cams or shoes 38 can be employed. As illustrated, I have utilized four cams or shoes 38 and the same are located adjacent to the periphery of the roll 11 and exactly 90° apart. Each cam or shoe is accurately positioned on the fluting roll relative to an adjacent fluting tooth and all of the shoes are positioned exactly the same relative to an adjacent tooth.

In operation of my strip feeding and guide means G and considering that the machine F is in operation and the rolls 11 are being rotated in the direction of the arrows (see FIGURES 1 and 2), then a strip is slid into the guide slot 19 with its rear end under the feed hook 27. When a cam or shoe 38 strikes the hook terminal 37 of the crank arm 31, the crank 29 will be rocked on its pivot 32 carrying the slide block 24 therewith against the tension of the spring 36. The slide block with its hook 27 will accurately forward and position the strip S between the rolls 11 and 12 and such strip will be accurately fluted thereby. As soon as a cam or shoe rides past the crank arm 31, the crank arm and the slide block will be quickly returned to its normal position by the spring 36 and at this time, another strip can be placed in position.

A stop 42 is carried by the mounting bracket for limiting the outward swinging movement of the crank 29 by the spring 36.

From the foregoing description, it can be seen that I have provided a simple but positive attachment for a medium fluter F to accurately feed strips into the machine so that all of the strips will be fluted identically.

Changes in details may be made without departing from the spirit or the scope of this invention but what I claim as new is:

1. In a medium fluter of the type embodying a pair of inter-meshing rotatable fluting rolls; an attachment for automatically feeding and guiding a strip on edge into and between the rolls including a guide having a tapering nose extending into the machine and between the rolls having a guide slot for receiving a strip on edge to be fluted, a slide block reciprocally carried by the guide having a feed hook for engaging the rear end of a strip placed in the slot, and means for reciprocating the slide block in the guide for feeding a strip in the slot into and between the rolls in an exact time relation relative to the teeth on said rolls embodying a crank pivotally supported at one end on the guide and including an arm extending partially over an edge of one roll, means operatively connecting the crank with the block, means normally holding the

crank and block in one position, and at least one cam shoe carried by the last mentioned roll for engaging and operating the crank to slide the block during the rotation of the roll.

5. 2. In a medium fluter of the type embodying a pair of inter-meshing fluting rolls; an attachment for feeding and guiding a strip to be fluted on edge between and into the fluting rolls including a guide having a tapered nose extending into the machine and leading between the rolls and having a guide slot opening out through its inner end for receiving a strip on edge, a slide block reciprocally mounted in said guide and having a feed hook on its outer end for engaging and receiving the outer end of a strip placed in the slot, a crank rockably carried by the guide, a pin and slot connection between the slide block and crank whereby upon movement of the crank the slide block will be carried therewith, spring means normally holding the crank and slide block in one position with the feed hook disposed to receive a strip and with an arm of the crank positioned partially over an edge of one fluting roll, and at least one cam shoe carried by the last mentioned fluting roll for engaging the arm of the crank for carrying said crank therewith against the tension of the spring for moving the slide block toward the fluting rolls for feeding a strip engaged by said hook into and between said rolls.

3. In a medium fluter as defined in claim 2 and said mentioned arm of the crank being adjustable to accurately position the same relative to the cam shoe.

30 4. In a medium fluter of the type embodying a pair of inter-meshing rotatable fluting rolls, an attachment for feeding and guiding a strip to be fluted on edge into and between said rolls including a guide extending into the machine having a forwardly tapered nose positioned between said rolls and having a guide slot for receiving a strip to be fluted on edge, a slide block reciprocally mounted in said guide and having a strip engaging hook on its outer end for moving said strip upon inward movement of the block in said guide between the rolls, 40 a crank rockably mounted at its outer end on said guide, a pin and slot connection between said crank and slide block whereby upon movement of the crank the slide block will be moved therewith, spring means normally holding the slide block and crank in one position with the hook ready to receive the outer end of a strip, cam shoes rigidly secured to one face of one fluting roll and said cam shoes being equidistantly spaced and all positioned exactly the same relative to an adjacent fluting tooth of the roll, and said crank having an arm disposed in the path of the movement of the cam shoes whereby upon rotation of the rolls the crank will be carried therewith for a partial rotation of the rolls to slide the slide block with its hook and strip toward the rolls.

5. In a medium fluter of the type including a pair of rotatable inter-meshing rolls; an attachment for feeding and guiding a strip on edge automatically into and between the rolls including a pair of facing guide blocks rigidly secured to the machine spaced for a portion of their length to define a guide slot for receiving a strip to be fluted on edge, the forward ends of said guide blocks being tapered and leading toward and between the rolls, one of said guide blocks being channeled and slotted, a slide block mounted in the channel for reciprocating movement having a strip feed hook on its outer end slidably in the slot in said block, a mounting bracket rigidly secured to one block and extending over the slot defined by the two blocks to further function as a guide for a strip, a crank including a long arm and a short arm extending at right angles to the long arm, means rockably mounting the outer end of the long arm on the mounting bracket, means operatively connecting the crank with the slide block including a pin and slot connection between the crank and slide block, the inner end of said short arm terminating in a hook, cam shoes equidistantly spaced carried by one face of one fluting roll, and spring means

60 65 70 75

normally holding the slide block at the outer end of the slot with the feed hook positioned to receive a strip placed in the slot and with the short arm of the crank partially over the edge of the fluting roll carrying the cam shoes and in the path of movement of the cam shoes whereby said cam shoes will actuate said crank.
